UNITED STATES PATENT OFFICE.

HENRY B. KEIPER, OF LANCASTER, PENNSYLVANIA.

DESIGN FOR A GEAR-TRAIN CASING FOR ROTARY BLOWERS.

SPECIFICATION forming part of Design No. 34,882, dated July 30, 1901.

Application filed June 8, 1901. Serial No. 63,804. Term of patent 14 years.

To all whom it may concern:

Be it known that I, HENRY B. KEIPER, a citizen of the United States, residing at Lancaster, in the county of Lancaster and State of Pennsylvania, have invented and produced a certain new, useful, and original Design for Gear-Train Casings for Rotary Blowers; and I do hereby declare the following to be a full, clear, and exact description of the invention, such as will enable others skilled in the art to which it appertains to make and use the same.

In the accompanying drawing, which forms a part of this specification, I have illustrated a perspective view of a gear-train casing for rotary blowers embodying my new design.

As shown in said drawing, the said casing consists of a main lower portion A, with an upper portion B resting thereon, giving the appearance to said parts of being divided on a line extending from the rear of the casing to the front thereof, at which point said main portion is provided with an attaching plate or flange C, having suitable apertures therein to receive the fastening bolts or screws, by which the casing may be secured to an adjacent blower-casing. The said main portion is also shown as having a tubular portion D at its base to receive the shaft of the blower, with a rib or protuberance thereon for engagement with or between suitable clamping devices, by which the gear-casing may be

mounted upon and secured to a stand or support therefor, the bore of said tubular portion extending through the attaching-plate C, as shown at d. Said main portion is also shown with a plurality of tubular bosses or projections A' to receive the bearings for the ends of the shafts of a train of gears within the casing.

As will be seen, the leading or material feature of my design resides in the gear-train casing having the appearance of being formed in separable portions mounted one upon the other and provided with tubular bosses or projections and a tubular base portion, together with a front attaching-plate, adapting the casing to be secured to a rotary fan-blower casing, with its shaft journaled in said tubular base portion.

Having thus described my invention, what I claim as new, and desire to secure by Letters Patent of the United States, is—

The design for a gear-train casing for rotary blowers, substantially as shown and described.

In testimony whereof I affix my signature in presence of two witnesses.

HENRY B. KEIPER.
